Attorney.

UNITED STATES PATENT OFFICE

2,236,038

HONING OR SHARPENING DEVICE FOR
CLOTH CUTTING MACHINES

Jacob Silberstang, New York, N. Y.

Application August 5, 1938, Serial No. 223,177

5 Claims. (Cl. 51—250)

The present invention relates to an improvement in cloth cutting machines and has for its principal object the provision of means thereon, substantially permanently mounted thereto, of a knife sharpening means, whereby, as required, from time to time, the knife edge may be sharpened or honed.

One of the main features of the present improved structure is that the sharpening of the blade is accomplished by a sharpening means which is moved to the blade and simultaneously contacts on both sides and bottom edge thereof, the sharpening being accomplished by the normal reciprocation of the blade against the fixedly held sharpening means. Thus the blade may be quickly and automatically brought to a keen cutting edge, without stopping the machine and without any grinding movement of the normally stationary sharpening means, other than to radially move it into and out of knife edge engagement.

A further feature of advantage in the present improvement is that the present sharpening means acts as a blade guard, protecting the operator from accidentally touching the blade edge, the blade cutting edge being also protected thereby from inadvertent damage.

A further feature of advantage is that the present sharpening means also mounts the presser foot, the presser foot and its attached blade grinding or sharpening means are vertically movable to accommodate the varying thickness of the pile of cloth being cut.

A further feature of advantage lies in the provision of means for locking and releasing the sharpening means and its presser foot in any adjusted upward position when first entering the knife towards the cloth to be cut.

A further improvement relates to the manner in which the sharpening elements are automatically and normally held out of blade sharpening position and the manner of arrangement of the said elements upon the guard frame.

An outstanding function of the instant structure is its simplicity, ease of operation, its applicability to any existing cutting machine, new or old. The present improvement does not, of itself, require the use of separate driving means or prime mover.

A further feature of advantage is in the provision of two separated, pivotally and vertically mounted shafts upon which are mounted a plurality of outstanding bracket arms on the outer ends of each of which are removably mounted abrasive blocks or hones, which blocks during

the sharpening operation, simultaneously contact on both faces of the blade edge, in balanced pressure. The blocks or hones, being removably mounted may be reversed in their bracket or arm ends, as one side of the sharpening face wears away, and thus be quickly renewed.

A further feature of advantage lies in the use of plural hones, these being vertically spaced apart from each other on the same shaft support and being spaced apart, alternately, from each other on their respective pivotal shafts. The vertical spacing or pitch of the hone pieces between each other and on each shaft is less than the stroke of the blade, so that normal reciprocation of the blade causes all of the blade edge to be honed or ground.

A further feature of advantage is in the provision of means between the hone holding arms and their respective shaft mountings whereby the faces of the hones may all be adjustably aligned to contact on both sides of the ground face of the cutting blade, evenly and simultaneously. As constructed and operated, the hones are flat faced and due to the manner of mounting them on the arms, which are slightly flexible, the hones contact with the ground faces of the blade at a narrow angle, as will be hereinafter pointed out in detail.

Means are also provided whereby the hones are normally and resiliently held out of operative honing position when not in use, being held forwardly of the cutting blade and being manually adjustable for moving the hones to honing position on opposite sides of the blade cutting edge.

The foregoing and other features of advantage will be apprehended as the herein description proceeds, and it will be obvious that modifications may be made in the structure herein, without departing from the spirit hereof or the scope of the appended claims.

In the drawing—

Fig. 1 is a view in elevation of the cutting machine and honing means;

Fig. 2 is a fragmentary front view, in elevation, of the upper part of the honing means;

Fig. 3 is a fragmentary view of the side opposite to that shown in Fig. 1, showing the hone carrier latching and release means;

Fig. 4 is a fragmentary side view of the hone, hone arm and carrier shaft;

Fig. 5 is an end view of the hone and gripping means as viewed from the right hand side of Fig. 4;

Fig. 6 is a sectional view, taken on the line 6—6, Fig. 1, looking in the direction of the arrows;

Fig. 7 is a fragmentary view, in front elevation, of the manual means for controlling the hones;

Fig. 8 is a sectional view in plan, taken on line 8—8, Fig. 1, looking in the direction of the arrows; and

10 Fig. 9 is a plan view of the presser foot removed from its operative position on the reciprocating hone holding guide.

In general, most of the cloth cutting machines comprise an electric motor M, which is connected to a vertical standard or knife guide S, by an intermediate connection or motor base N, Fig. 1. The standard S is grooved as at o, Figs. 1 and 8, to guide a vertically reciprocating, angled face knife k. The upper end of the knife 15 k is connected to a motor driven rotary means, not shown, but is well known in this art. The motor and knife standard connecting means is provided with the usual horizontal handle H, broken for convenience, Fig. 1, whereby the 20 cutter is manually directed against the cloth to be cut.

The knife standard or guide S is firmly mounted in a base plate B of the customary kind. All of the foregoing noted parts are substantially standard to cloth cutting machines, are well known and it is thought, need no further detailed description.

The front face plate 7 of the motor M, Figs. 1, 2 and 6 is provided with two opposed Z-shaped 25 guide strips 4 and 5, these being held to said plate 7 in spaced operative position by screws 6—6, Figs. 2 and 3. The strips 4 and 5 are so located as to form a gibway in which is slidably mounted an H-shaped, elongate gib piece 3, 30 which is of such a length as to permit its attached presser foot F to extend and rest upon the base B and to be fully supported by the gibway at its upper end while in the lower position of rest.

45 The presser foot F of well known construction, may be affixed to the lower end 32 of the gib 3 by any suitable means.

As shown in Figs. 2 and 3, one flange or rib 21 of the H-shaped gib 3 is provided with rack teeth 50 T along its entire length and this toothed section with its opposite rib 20, slide in the slide grooves formed by the guide strips 4 and 5.

A manipulating knob N' is affixed at the upper end of gib 3, to enable the user to raise and lower 55 the gib 3, as desired.

At the front side of support N, Figs. 2 and 3, is located a bearing block 39, which is secured to the slide 5 by screws 40—40, said bearing 39 slidably supporting a toothed detent 38, the inner 60 end of said plunger being provided with teeth, which mesh with the teeth T on said gib 3. The outer end of said plunger 38 is provided with a yoke Y and in this yoke is pivotally mounted, by a pin 41, to one arm 36 of a hand lever, the opposite end of said lever having a twisted section 37 to form a flat manipulative handle, which extends downwardly at a slight angle, so as to be located adjacent the cutting machine handle H, for convenience in manipulating, Figs. 2—3.

70 The lever portion 36 is pivoted in a trunnion block 33 by a pin 34, said block being affixed to the support N by screws 33'—33', Fig. 3. Thus the lever 36—37 is pivoted adjacent the toothed detent 38, so that said detent may be reciprocated in the bearing 39, to hold or release the gib

rack 3 in any upper or lower position of vertical adjustment.

The hand lever 36—37 is spring actuated to normally keep the toothed detent 38 in meshed contact with the gib-rack 3, and to this end, a 5 compressible coiled spring 35, Fig. 3, is connected between the arm 36 and the trunnion block 33. Squeezing the lever arm 37 towards the handle H releases the gib-rack and its appurtenant parts.

From the foregoing it will be seen that the gib- 10 rack 3 and its presser foot F may be moved up and down, as indicated by dotted lines F, Fig. 1, carrying with it the knife sharpening means mounted thereon, as will now be described.

The front face of the gib-rack 3, as will be 15 seen in Figs. 1 and 7 mounts an angle bracket bearing 8, to form an upper bearing for two vertically aligned, rotatable shafts 10—11, Fig. 7. The bearing ends of shafts 10—11 may be reduced in diameter as at 15 and 16. Below the 20 bearing 8, the shafts are provided with two intermeshing gears 12 and 13. The reduced end 15 of shaft 10 is extended and mounts thereon a hand operated lever 18, the hub 17 of which is suitably affixed to the shaft extension 15. A 25 coiled spring 14 is mounted over extension 15, and has one of its ends fixedly caught on hub 17. The other end of said spring being extended and caught on the short extending end of shaft end 16. This arrangement causes the lever 18 to be 30 normally and resiliently held in the retracted position shown in Figs. 1 and 6.

The lower end of the gib-rack 3 also has a fixed angle bracket bearing 9, which rotatably supports the lower reduced or shouldered ends of 35 shafts 10 and 11, as can be seen in Fig. 1. Thus the parallel shafts 10 and 11 are rotatable in opposite directions simultaneously by reason of the meshed gears 12 and 13 fixed thereon, when the handle 18 is manipulated to the dotted position 40 shown at A, Fig. 6.

Each of the shafts are provided with a plurality of slightly resilient sheet metal arms 24, these arms being right and left handed in their mounting on each shaft.

The arms generally denoted by 2 and 2', are 45 made, preferably, of flat sheet metal to obtain a certain amount of side resilience when the hone pieces 22 contact with the blade edge.

The arms are each provided at one end with 50 a quill ended, shaft embracing curl 25, Figs. 4 and 8, and, as seen in Fig. 4, are downwardly offset at 24. The opposite end of each arm is formed a hone embracing jaw or clip 23, which is so bent as to provide two opposing, resilient 55 hone gripping lips a—a. These lips are spaced apart, and are resiliently further spread apart upon the introduction of a rectangular hone piece 22 therebetween, such assembly being shown in Figs. 4 and 5.

The hone pieces are preferably made of a suitable abrasive stone of suitable grain, and are each provided with opposed, longitudinal side grooves 22' and 22'', into which the lips a—a compressively engage, to thereby removably hold 65 the hones in operative blade edge honing position. The hones are shown as being rectangular, but they could be of any other operative outline or contour. By the hone and jaw construction above described, when the sharpening or honing 70 surface of hone 22 becomes glazed or worn, the hone may be withdrawn and be reversely inserted with its opposite honing face exposed, or a new honing piece inserted in the jaw 23.

In order to provide means for adjustably and 75

operatively mounting the honing arms 2 and 2' to the shafts 10 and 11, the quills 25 are provided with two parallel, elongate slots 26-26 near their ends and after snapping the quills onto the shafts 10 or 11, two screws 27-27 are screwed into the shafts through the said elongate slots, and, after radially adjusting all of the arms on each shaft into blade contacting alinement, the screws 27 are firmly tightened on the quills. This construction permits of individual radial adjustment of each hone and hone arm, if desired. This latter feature of radial adjustment, as will be seen dotted, Fig. 8, brings all of the honing faces in such position that they all contact, simultaneously on opposite sides 15 of blade k at and near the cutting edge E, to produce an even contact of all of the hones along the entire operative length of the cutting edge.

The hone holding arms on each shaft 10 or 11 are mounted in a relatively staggered arrangement as will be seen in Fig. 1, where the hone arms 24 and hones 22 are held in non-operative position away from the knife by the spring 14, as previously described. In Fig. 1 the lowermost first arm 2', which is located on shaft 10 is spaced from 25 its next upper, successive arm 2', and this spacing continues on the other arms 2', on shaft 10. As thus shown the honing faces of the hones 22 are faced towards the viewer.

The hone arms on shaft 11 are each located 30 between the spaces of the hone arms on shaft 10, and vice versa, and thus the hone arms on each shaft 10 and 11 are alternated or staggered. As viewed in Figs. 6 and 8, when the hone arms are in non-operative position, the outer hone ends of 35 2 and 2' pass one another, at their extremities into the spaces between each row of hone arms. Thus the faces of the hones 22 on the shaft 11 face away from the viewer, as shown in Fig. 1.

In Figs. 6 and 8, when the hone arms and hones 40 are back in non-operative position the honing faces are exposed, but when the arm 18 is swung one hundred and eighty degrees, approximately, to the dotted position, in Fig. 6, the hone arms are moved to the dotted positions shown in Figs. 45 1 and 8, with the honing faces in contact with the blade k.

A further feature of advantage will be noted 45 by a study of Fig. 8, in which the blade contacting hones embrace the angular blade k at its angular face planes, shown dotted, so that the blade wears back at its natural angle as it is repeatedly sharpened.

When the opposed honing devices are brought 50 to the blade as shown dotted in Fig. 8, the blade is permitted to oscillate at its customary speed and the blade is thus rubbed up and down against the stationary hones, to which pressure may be applied by the handle 18.

Due to the construction and location of this 55 sharpening device, with the presser foot F, resting on the base B, the operative reciprocation of the blade brings up the lower, under, angled cutting edge L, Fig. 1, into such position upwardly as to cause said cutting edge to be also automatically sharpened as it alternately contacts with the two lower, opposed hones.

It will thus be seen that the sharpener as applied and operated is simple in construction and speedy in operation, and in nowise interferes with 60 the operation of the cutter.

Having thus described the invention what is claimed is:

1. In combination, a cloth cutter having a vertically reciprocating knife, a gib, guide means for 65 slidably supporting the gib for vertical movement

in front of said knife, two rotatable shafts mounted for rotary movement on said gib, each shaft having a row of outstanding radial arms mounted thereon, said arms having resilient hone holding jaws, each jaw mounting a hone; and means between said arms and said shafts for providing radial alining adjustment therebetween. 5

2. The combination with a cloth cutter having a vertically reciprocating knife, knife sharpening means including a slidable gib, guide means on 10 the cutter for slidably supporting the gib for vertical operation in front of said knife, a presser foot carried by said gib, two rotatable shafts mounted for rotary movement on said gib, each shaft having a row of outstanding arms mounted thereon, 15 said arms having resilient hone holding jaws, each jaw mounting a removable reversible, non-rotatable hone.

3. The combination with a cloth cutter having a vertically reciprocating knife, knife sharpening 20 means, including a slidable gib, guide means for slidably supporting the gib for vertical operation in front of said knife, a presser foot carried by said gib, a pair of opposed, dual bearings spacedly mounted upon said gib, a pair of spaced parallel 25 shafts vertically mounted in said bearings and adapted to be moved with said gib, a plurality of groups of hone carrying means adjustably carried on each said shafts in normally staggered relation to the arms on the other shaft, each of said hone carrying arms being provided with a non-rotatable, removable hone and means on and between said shafts for simultaneously and radially moving said hones to opposite faces of said blade. 30

4. The combination with a cloth cutter having 35 a vertically reciprocating knife, knife sharpening means, including a slidable gib, guide means for slidably supporting the gib for vertical operation in front of said knife, a presser foot carried by said gib, upper and lower bearings on said gib, a 40 pair of vertical shafts mounted in said bearings; a group of resilient outstanding arms mounted in one row on each shaft, means between said arms and said shafts for providing radial alining adjustment therebetween, each arm having a resilient hone supporting jaw thereon at its outer end and hones located in each said jaw, said hones on each row of arms being faced normally outward when in non-operative position, and means for rotating the shafts to carry the hones from 45 the non-operative contact with said knife to operative honing contact therewith. 50

5. The combination with a cloth cutter having a vertically reciprocating knife, knife sharpening means, including a slidable gib, guide means 55 for slidably supporting the gib for vertical operation in front of said knife, a presser foot carried by said gib, a dual spaced apart knife honing means; means for mounting said dual knife honing means on said gib normally out of operative 60 contact with said knife and movable into contact with the knife, and manual means for causing said honing means to contact on both sides of the cutting edge of said knife during reciprocation of the blade, said slidable gib being provided on one of its edges with a toothed rack section, and a control lever movably and pivotally mounted adjacent thereto, said lever having a pivoted, slideable, toothed latch manually engageable with said rack portion whereby to lock said gib and its 65 fixed associate presser foot and honing means in any adjusted position and to release said gib and associate members from their latched adjusted position. 70
